UNITED STATES PATENT OFFICE.

JOSEPH H. MARTIN, OF ELGIN, ILLINOIS.

WATCHMAKER'S GAGE.

1,101,945.

Specification of Letters Patent. Patented June 30, 1914.

Application filed June 12, 1912. Serial No. 703,152.

To all whom it may concern:

Be it known that I, JOSEPH H. MARTIN, a citizen of the United States, and a resident of the city of Elgin, county of Kane, and State of Illinois, have invented certain new and useful Improvements in Watchmakers' Gages, of which the following is a specification.

My invention relates to watch makers' gages, and more specifically to improvements in balance wheel truing devices adapted for use by watch makers in effecting the truing of balance wheels of watches.

The object of my invention is the production of a gage of the character mentioned through the medium of which a balance wheel may be readily and expeditiously adjusted and in which various adjustments will be afforded so as to adapt the device for use in conjunction with balance wheels of various dimensions.

A further object is the production of a device, as mentioned, which will be durable and economical in construction and efficient in operation.

Other objects will appear hereinafter.

With these objects in view, my invention consists in the combinations and arrangements of parts, all as will be hereinafter described and claimed.

The invention will be best understood by reference to the accompanying drawing forming a part of this specification, and in which—

Figure 1 is a front elevation of a gage embodying my invention, Fig. 2 is an enlarged section taken on line $x-x$ of Fig. 1, Fig. 3 is a fragmentary section taken on substantially line $y-y$ of Fig. 2, Fig. 4 is an enlarged section taken on line $z-z$ of Fig. 1, Fig. 5 is an enlarged perspective view of the gage-finger of the device, detached, Fig. 6 is an enlarged perspective view of the gage-finger supporting member detached, Fig. 7 is an enlarged fragmental detail of the gage.

The preferred form of construction, as illustrated in the drawing comprises a caliper consisting of pivotally connected members or levers which are formed to constitute coöperating clamping jaws 1 and 1' at the respective ends thereof. The outer ends of the jaws 1 and 1' are provided with bearings or journals 2 between which is adapted to be rotatably mounted the balance wheel 2' which it is desired to true.

Provided at one end of the caliper is a bar 3 one end of which is pivotally secured by means of a screw 4 to the corresponding jaw 1, the jaw 1 at the opposite end of the caliper being provided with a threaded socket 4' in order to accommodate said bar if it is desired to mount the same upon the opposite end of the caliper, the opposite ends of the caliper, being adapted in practice to accommodate balance wheels having spindles of different forms or sizes. A screw 5 coöperates with the screw 4, to serve as a means of locking the latter in position, as clearly shown in Fig. 2. The screw 4, in use, will be so adjusted as to exert a pressure upon the bar 3 sufficient to hold said bar in positions of angular adjustment to which the same may be moved by the fingers in operating the device.

Mounted upon the front side of the bar 3 is a supporting member 6, the same being secured to said bar by means of a screw 7, a nut 7' and washer 8 so as to permit of rotary adjustment of said member, an elongated slot 9 provided in the bar 3 for engagement by said screw and nut permitting of adjustment of said supporting member longitudinally of said bar. The opposite sides of the nut 7' are flattened, as at 10 for engagement with the opposite sides of slot 9 which thereby serve as a means of preventing relative rotary movement of said nut during the adjustment of the screw 7 therein.

One end of the supporting member 6 is bifurcated, for the support of the gage-finger 11, the rearward end of which is pivotally mounted between the branches 6' of said supporting member. A screw 12 projects through the branches 6' and the corresponding end of finger 11 for pivotally connecting the latter with the supporting member, said screw passing loosely through one of the branches 6' and the finger 11 and being threaded in the other of said branches so that by adjusting said screw, clamping of the gage-finger between the branches 6' may be effected so as to frictionally hold said finger in position of adjustment.

With a construction as set forth, it will be seen that a variety of adjustments is afforded so as to permit of the gage-finger being adjusted to any position desired in effecting the truing of the balance wheel positioned in the caliper. The various parts are frictionally held in positions of adjust-

ment so that the same will yield to manual pressure and permit of ready and expeditious adjustment during operation of the device. The construction is such that the friction 5 may be increased at any or all of the points so as to take up wear, or to secure any friction suitable to the individual convenience of the operator. The outer end of the gage-finger 11 is concave, as at 13, so as 10 to conform with the convex curvature of the periphery of the balance wheel.

At a right angle to curved surface 13 is a plane edge portion on gage finger 11 parallel with the plane sides of balance wheel 2'. 15 Finger 11 is disposed with relation to the balance wheel 2' so that the corner of curved surface 13 and the plane edged portion of said finger is spaced very close to and parallel with the corner between the periphery 20 and one plane side of said balance wheel. Obviously, with this arrangement the balance wheel may be gaged for its being true both as to its concentricity and its being perpendicular with its shaft, see Figs. 1 25 and 7.

The device is durable and economical in construction, and will be found highly efficient in use.

While I have illustrated and described 30 the preferred form of construction for carrying my invention into effect, this is capable of variation and modification without departing from the spirit of the invention. I, therefore, do not wish to be limited to the 35 precise details of construction set forth, but desire to avail myself of such variations and modifications as come within the scope of the appended claims.

Having described my invention what I 40 claim as new and desire to secure by Letters Patent is:

1. In a device of the class described, a pair 45 of pivotally connected jaws provided with coöperating bearings at the ends of said jaws; a bar pivotally mounted upon one of said jaws; a gage-finger supporting member mounted for longitudinal and rotary adjustment upon said bar; and a gage-finger mounted for rotary adjustment in said sup- 50 porting member, substantially as described.

2. In a device of the class described, a pair of pivotally connected jaws provided with coöperating bearings at the ends of said jaws; a bar pivotally mounted upon one of said jaws; a gage-finger supporting member mounted for longitudinal adjustment upon said bar; one end of said supporting member being bifurcated; and a gage-finger having its rearward end mounted for rotary adjustment in said bifurcated end of said supporting member, substantially as described. 55 60

3. In a device of the class described, a pair of pivotally connected jaws provided with coöperating bearings at the ends of 65 said jaws; a bar pivotally mounted upon one of said jaws; a gage-finger supporting member mounted for longitudinal and rotary adjustment upon said bar; means passing through said bar and engaging an elongated 70 longitudinally extending slot provided in said bar for frictionally holding said supporting member in positions of adjustment upon said bar; and a gage-finger carried by said supporting member, substantially as de- 75 scribed.

4. In a device of the class described, a pair of pivotally connected jaws provided with coöperating bearings at the ends of 80 said jaws; a bar pivotally mounted upon one of said jaws; a gage-finger supporting member mounted for longitudinal adjustment upon said bar; one end of said supporting member being bifurcated; a gage- 85 finger having its rearward end mounted for rotary adjustment in said bifurcated end of said supporting member; and adjustable means passing through the arms of said bifurcated end of said supporting member and said end of said finger for clamping said 90 finger between said arms, substantially as described.

In testimony whereof I have signed my name to this specification in the presence of two subscribing witnesses.

JOSEPH H. MARTIN.
